H. E. YOCUM.
LINING FOR PRESERVING VESSELS.
APPLICATION FILED FEB. 27, 1917.

1,265,858.

Patented May 14, 1918.

UNITED STATES PATENT OFFICE.

HARRY E. YOCUM, OF HANCOCK, MARYLAND.

LINING FOR PRESERVING VESSELS.

1,265,858.

Specification of Letters Patent. Patented May 14, 1918.

Application filed February 27, 1917. Serial No. 151,304.

To all whom it may concern:

Be it known that I, HARRY E. YOCUM, a citizen of the United States, residing at Hancock, in the county of Washington and State of Maryland, have invented certain new and useful Improvements in Linings for Preserving Vessels, of which the following is a specification.

This invention relates to an improved lining for preserving cans or other preserving vessels and has as its primary object to provide a lining which may be arranged within substantially any conventional type of preserving can, as now in common use, to form a container for the contents thereof preventing contact of the said contents with the metal of the can and thus minimizing the chemical action of the said contents upon the can with its resultant effect upon the natural taste of the said contents.

The invention has as a further object to provide a lining so formed that it may be readily fitted into the container.

And the invention has as a still further object to so construct the lining that it may be easily struck as a blank by a single operation.

Other and incidental objects will appear as the description proceeds and in the drawings wherein I have illustrated the preferred embodiment of the invention and wherein similar reference characters designate corresponding parts throughout the several views:

Figure 1 is a sectional view showing my improved lining arranged within a conventional type of preserving can and illustrating the manner in which the said lining is formed to completely inclose the fruit within the can.

Fig. 2 is a transverse sectional view showing in dotted lines, the manner in which the sections of the top flap of the lining are arranged to coöperate for closing the can at its upper end, and

Fig. 3 is a perspective view particularly showing the blank from which the lining is formed and illustrating in dotted lines, the manner in which the sections of the top flap are moved with respect to each other so that the said flap may be easily inserted within the top of the can.

In carrying out the invention, my improved lining is formed from a blank of the type particularly shown in Fig. 3 of the drawings. This blank includes an elongated

body 10 of equal width from end to end. Formed on the lower edge of the body 10 adjacent one extremity thereof is a substantially circular bottom flap 11 which, at its juncture with the body, is provided with a transverse fold line A and formed on the upper edge of the body opposite the said flap is a top flap 12. The top flap 12 is also substantially circular and is slit diametrically from the body 10 to divide the said flap into coacting sections. At the inner extremity of the said slit, the body is provided with a notch or slit 13. The purpose of this slit will presently appear.

In positioning the flaps 10 and 11, adjacent one extremity of the body, the said body thus provides a relatively short flap 14 at one side of the flaps 10 and 11 and a relatively long flap 15 at the opposite side thereof. The blank, as thus formed, is preferably formed from a single piece of paraffin paper or other similar material and it will be observed that the blank is of such nature that it may be struck from the stock at one operation.

In Figs. 1 and 2 of the drawings, I have illustrated my improved lining in connection with a conventional type of preserving can. This can is formed with a cylindrical body wall 16 and is closed at one end by a bottom wall 17. At its opposite end, the can is provided with a head 18 for receiving the can top 19, this top, as is usual, hermetically sealing the can.

In fitting the lining within the can, the bottom flap 11 is first folded up toward the inner face of the body 10 of the lining at the fold line A when the short flap 14 of the body is turned inwardly toward the long flap 15. The long flap 15 is then folded about the short flap to form the body into a cylinder with the top flap 12 projecting upwardly from the upper edge thereof. This cylinder is contracted until it will easily fit through the open end of the can and is moved downwardly therein until the bottom edge of the said cylinder abuts the bottom wall 17 of the can. The flaps 14 and 15 of the body 10 are then released when the resiliency of the lining will spring the said flaps outwardly to expand the cylinder until the body of the lining is engaged close against the cylindrical body wall 16 of the can. With the body of the lining thus in position to form a container body within

the can, the bottom flap 11 is bent downwardly at the fold line A to snugly close the lower end of the said container body and overlie the bottom wall 17 of the can with the top flap 12 projecting out through the open end of the can in the manner illustrated in dotted lines in Fig. 1.

The can is then ready to be filled in the usual manner and upon being so filled, 10 the sections of the top flap 12 are moved to overlie each other as shown in dotted lines in Fig. 3 when the said flap may be easily inserted through the open end of the can and into the upper end of the container. 15 Consequently, upon the release of the said flap sections, the said sections will move to assume their normal position with their inner edges abutting, as shown in dotted lines in Fig. 2, to close the said container at 20 its upper extremity. The can top 19 is then applied to hermetically seal the can.

Preferably, the top flap 12 is of a diameter slightly less than that of the bottom flap 11 and in order to prevent wrinkling of the 35 body 10 of the lining when the sections of the flap are moved into overlapping relation to be inserted into the upper end of the container, the slit 15 is formed at the inner extremity of the dividing line between the 40 said sections. The purpose of this slit, therefore, now becomes apparent and it will be observed that the said slit will also tend to prevent any tearing of the flap sections at their juncture with the body 10 35 of the lining when being moved relative to each other.

It will, therefore, be seen that the lining may be easily placed within the can and attention is directed to the fact that the said 45 lining is formed to completely inclose the contents of the can so that the said contents or fruit cannot contact with the can to chemically act thereon and affect the natural taste of the said fruit. I conse-

quently provide a particularly efficient construction for the purpose set forth. 45

Having thus described my invention, what I claim and desire to secure by Letters Patent is:

1. The combination with a cylindrical 50 preserving vessel, of a lining therefor including an elongated body having its extremities free and slidably overlapped to provide a container fitting within the receptacle to normally expand against the 55 cylindrical wall thereof, and top and bottom flaps projecting from the side edges of the body at oppositely disposed points adjacent one end of the body, the bottom flap being solid and entirely closing the bottom 60 of the said container resting upon the bottom wall of the vessel and the top flap being bent inwardly upon the body to removably fit within the upper extremity of the container and formed of coacting halves having 65 straight confronting edges meeting to entirely close the upper end of the container.

2. A lining for preserving vessels formed from a blank including an oblong body having parallel side edges and parallel end edges, 70 there being a single top flap projecting beyond one side edge of the body and a single bottom flap projecting beyond the opposite side edge, the said side edges being interrupted at opposite sides of said flaps and the 75 said flaps being arranged at oppositely disposed points adjacent one end of the body to coöperate therewith for closing opposite ends of a container formed by slidably over-lapping the extremities of 80 the body, the bottom flap being solid and the top flap being split into coacting halves adapted to be overlapped upon each other for insertion into the adjacent end of the container. 85

In testimony whereof I affix my signature.

HARRY E. YOCUM. [L.S.]
